(57) CLAIM

The ornamental design for a novelty attachment for panty waistband, as shown and described.

DESCRIPTION

FIG. 1 is a left elevation view of a novelty attachment for panty waist band showing my new design.

FIG. 2 is a perspective view thereof; and,

FIG. 3 is a front elevation view thereof.

The broken line showing of human form and clothing articles is included for the purpose of illustrating environment and forms no part of the claimed design.
